SHAKING CONVEYER

Hans Cremer, Bochum, Germany, assignor to
Gebr. Eickhoff, Maschinenfabrik und Eisen-
giesserei, Bochum, Germany

Application January 12, 1935, Serial No. 1,566
In Germany January 20, 1934

8 Claims. (Cl. 74—26)

The invention relates to shaking conveyers and has particular reference to the drive of such conveyers.

In order to damp the shocks occurring in the 5 operation of shaking conveyers, which are driven by means of a rotary motor, such as an electric motor or a rotary compressed air motor, a spring attachment is interposed usually between the conveyer and the gear. Such spring attachment, 10 however, has not the correct power for the various conditions of service, since the forces to be transmitted by the spring attachment to the conveyer depend upon the length of the conveyer concerned and upon the quantity of goods 15 to be conveyed by it, that means, upon the masses to be moved by the conveyer in the special case, which frequently vary within comparatively wide limits. Now, an adoption of the spring power to the forces of motion to be transmitted to the 20 shaking conveyer cannot be obtained by varying the tension of the spring, since the so-called "spring-constant", that is the proportion of the power to the stroke of the spring, cannot be altered by altering the tension. Consequently, 25 the effect of a determined spring arrangement is in every case only satisfactory within determined limits, that means, within determined conveyer lengths and determined quantities of the goods 30 to be conveyed, while outside these limits the favorable effect of the spring attachment degen- 35 erates into a noxious effect which may lead to disturbances of the conveying work and destruction of the springs themselves. Such destructive effect arises in particular if the critical number of oscillations, which decreases with increasing 40 mass, becomes smaller than the number of the driving strokes, that is, if the critical number of oscillations of the oscillating system formed by the spring attachment and the conveyer with 45 larger masses of the conveyer and of the goods to be conveyed is reached by the rate of driving strokes. In order to render possible such an adoption of the springs to greater lengths of the conveyer and, in particular, to prevent surpassing 50 of the critical number of oscillations, one must, for greater conveyer lengths or for conveying larger masses of goods, either reduce the number of strokes of the drive, which would be very troublesome and expensive in the drive by 55 alternating current employed in the most cases, or springs of a greater constant would have to be used, the exchanging of which would be very troublesome during service.

The object of the invention, therefore, is a spring attachment for shaking conveyers in which

an alteration of the spring constant is possible without exchange of the springs. This object is obtained according to the invention by a spring attachment in which a reciprocating gear part is arranged between, and acts upon two springs 5 of the same direction of action. In known spring attachments of this type, the attachment at the same time serves to convert a sinusoidal gear motion, not suited for the motion of the conveyer, into the required motion, in which the conveyer 10 at the end of its conveying stroke is notably retarded. Thereupon the conveyer suddenly reverses its motion and at the end of its back stroke it comes gently to rest and is forwarded again with at least approximately uniform ac- 15celeration. To this end two springs of different constant are provided in the known conveyer gears, the spring of greater constant serving to effect the retardation at the end of the feed stroke. In order that now in this case the different constants of the two springs come into effect, it is necessary that that part of the gear, which 20 engages between the springs at any change of stroke, is lifted at least from one of the springs, since, if the two springs would be effective in 25 both directions, they would act as one sole spring of one permanently uniform spring constant.

For the purpose of disclosing my invention I have illustrated certain embodiments thereof in the accompanying drawing in which— 30

Figures 1, 2 and 3 are diagrams of the action produced by the springs;

Figure 4 is a side elevation partly in section of one form of the invention;

Figure 5 is a vertical section of another modi- 35 fication; and

Figure 6 is a plan view of a twin gear.

Figure 1 is a spring diagram and illustrates the mode of operation of this known spring attachment comprising two springs of different 40 constant, in which the part transmitting the driving force to the conveyer temporarily is lifted from one of the two springs. In this diagram c^1 denotes the constant of the strong spring which 45 temporarily is released in the stroke in the direction of feed, and c^2 denotes the constant of the weak spring. As long as the two springs are under tension, that means, the one spring is compressed more highly while the other spring is released correspondingly, this spring attachment 50 operates with the spring constant c^1+c^2 , and thereupon, that is, as soon as the gear part is 55 lifted from the strong spring c^1 , only with the constant c^2 . In the spring diagram of Figure 1 the line $y-y$ denotes the central position of the

spring attachment in which the two springs have equal initial tension. If, now, the gear part engaged and reciprocating between the two springs moves so as to compress the strong spring, while the weak spring is released correspondingly, the spring powers increase and decrease according to the left-hand half of the diagram. If, however, the gear part moves in opposite direction from the central position $y-y$, as illustrated in the right-hand half of the diagram of Figure 1, the strong spring is further released until it is lifted wholly from the gear part in the line $x-x$, so that thereafter only the weak spring is effective which continues to be compressed.

As to be seen in the diagram, now in the line $x-x$ the effect of the forces of the spring attachment is unsteady, which results in a shockwise stress of the gear. Furthermore, an alteration of the initial tension of the springs of this arrangement does not give an alteration of the spring constant of the attachment, that means, the spring attachment is not capable of being adapted to the action of widely varying forces of masses.

Here the invention offers a remedy. According to the invention, in contrast to the known spring attachment hereinbefore described, in lieu of two springs of different constant two springs are made use of having equal or at least approximately equal constants. In order that this spring attachment is capable of operating selectively with a smaller or a greater constant, according to the invention springs are used of such a power, that with a high initial tension both these springs remain under tension in both directions of motion. The spring coils do therefore not rest completely on one another, and none of the springs is lifted from the gear part engaged between them. On the other hand, if the springs have no or only a small initial tension, the one spring is released at least when the other spring begins to be compressed. The effect of such a spring attachment is as follows: Since the springs are initially not compressed, or only to a small extent, alternately one of the springs is released in the reciprocating motion, when the other spring begins to be compressed. This is the case when the two springs in the central position of the attachment abut against the intermediate gear part without play and without any or substantial initial tension. When this attachment is moved, as shown in the spring diagram of Figure 2, only one spring of the constant c^1 acts in the one direction, while only the other spring of constant c^2 acts in the other direction, these constants c^1 and c^2 being at least approximately equal to one another. Consequently, the change of force takes place steadily, as Figure 2 shows, that is, without causing knocking in the gear.

If, on the other hand, so great an initial tension is given to the springs, that the spring attachment is not lifted from any of the two springs in both directions of motion, so that both springs remain under tension in both directions, and if, in addition, the two springs are so strong, that their coils do not come to rest on one another even with the greatest occurring conveyer forces, that is, none of the springs become solid, but both springs remain elastic in both directions, the mode of operation of the spring attachment is as illustrated in the diagram shown in Figure 3. In the central position $y-y$ of the attachment as shown in this figure the two springs abut against the intermediate gear part with equal initial tension. If the gear moves from this central position in the one or other direction, the ten-

sion of the one spring increases, as shown in the diagram of Figure 3, and that of the other spring decreases correspondingly. The action of the spring attachment here is uniform in the two directions of motion and there is in every direction a spring constant of the amount c^1+c^2 , that is, provided that springs of equal or approximately equal constants and having twice the amount of springs without initial tension are used. The transmission of the power is also in this case steady, like in the case of springs under no initial tension, as to be seen in Figure 3.

The described construction of spring attachment is the first to enable an adaption of the action of such attachment with shaking conveyers within certain limits to the varying length of the conveyer and to the varying quantity of goods to be fed, both of which factors vary according to the conditions of service. This adaption is effected by an alteration of the spring constant, without an exchanging of the springs themselves, and merely by altering their initial tension.

Since in the present case the two springs have at least approximately equal constants, these springs in themselves do not produce the typical law of shaking motion. On the contrary, the intermediate gear has to be designed in these conveyers in such a manner, that the intermediate reciprocating spring plate or piston moves corresponding to the law of shaking motion. In other words, a great retardation and acceleration at the end of the feed stroke and a gently terminating back stroke, as well as a rather uniform and not too great acceleration up toward the end of the feed stroke of the conveyer is to be obtained. To this end the conveyer gear may be designed in any known manner.

In order now, that the invention may be clearly understood and readily carried into effect, three embodiments of shaking conveyers constructed according to the invention are illustrated in the accompanying drawing by way of example by the Figures 4, 5 and 6.

In the embodiment shown in Figure 4 the spring attachment comprises a cylinder 3 which at 2 is hingedly fixed to the shaking conveyer 1. In the cylinder 3 are disposed two springs 4 and 5 of equal or nearly equal power. A rod 6 is engaged by means of a collar or piston between the springs 4, 5, the other end of spring 5 abutting against the end wall 8 of the cylinder 3, while spring 4 abuts on its outer end against a cover 9 screwed into the cylinder and shiftable in axial direction. By displacing the cover 9 the tension of the springs 4, 5 can be adjusted uniformly in such a manner, that with comparatively short shaking conveyers the collar 7 is alternately lifted from the springs 4 and 5 immediately or shortly after its motion from the central position. With long conveyers the collar 7 remains in elastic close contact with both springs in both directions of movement. The power of the springs 4 and 5 has to be determined in such a manner, that the springs do not become solid even with the longest conveyers and the largest quantities of goods to be conveyed for which the spring attachment is intended.

In the embodiment shown in Figure 4 the gear serving to reciprocate the rod 6 in a manner giving a satisfactory conveying motion comprises a rotary motor 10, gear wheels 11, 12 actuated by it, a shaft 14 carrying an eccentric or crank, a rod 15, and a shaft 17 set in angular motion by means of a rock lever 16 mounted thereon.

These parts are enclosed in a casing 18, while outside the latter is mounted on shaft 17 another rock lever 19 hingedly fixed to the rod 6 and thus adapted to reciprocate the latter in the correct manner of motion, the collar 7 elastically transmitting the motion to the conveyer 1 through the intermediary of the springs 4, 5 and cylinder 3.

In the embodiment illustrated in Figure 5 the conveyer gear comprises gear wheels 21 and 22, an elliptic spur wheel 23 revolving with the latter and mounted in one of its foci 24, and a companion elliptic wheel 25 in mesh with wheel 23 and likewise mounted in one of its foci 26. It actuates a crank 27 which transmits its motion through a rod 28 to a crosshead 29. The latter is hingedly fixed to a cylinder 30 which like in the first-described embodiment includes two springs 31 and 32 disposed in alinement and having equal or nearly equal power. Between the springs is arranged a collar or piston 33 which is hingedly fixed to the conveyer 1 through a rod 34. For the purpose of uniformly adjusting the springs 31, 32 there is again provided an axially adjustable cylinder cover 30'. As may be seen in Figure 6, this gear may also be constructed as twin gear, by two rods 36, 37 with appurtenant crossheads 38, 39 being reciprocated according to the law of conveyer motion by the crank shaft 35 and acting upon two rods 40, 41 of the twin spring attachment.

It is to be understood, as a matter of course, that the actuating gear may also be designed in any other suitable manner, provided its action is such as to give a driving motion of the spring attachment favorable for the conveying effect of the shaking conveyer.

What I claim and desire to secure by Letters

Patent is:—

40 1. A drive for a shaking conveyer having a conveying member comprising a driving mechanism, said mechanism including a driving member which is moved according to the law of conveyer motion, and means connecting said driving member to said conveying member, said connecting means including elements pivotally connected to said driving member and conveying member respectively, a pair of aligned springs of equal strength and stroke, a member on one of said elements located between said springs, and means on the other element engaging the outer ends of the springs, said last member alternately compressing said springs in opposite directions, said springs remaining elastic when said compressing member is in compressing position, whereby the reciprocating and accelerating motions of the driving and connecting means and of said conveying member are modified and the change of force from one direction to the other takes place steadily and smoothly.

65 2. In a device according to claim 1, the means on said other element including a member, said member being longitudinally adjustable with respect to said springs for adjusting the tension of said springs uniformly with respect to each other.

70 3. In a device according to claim 1, the means on said other element including a member, said member being longitudinally adjustable with respect to said springs for adjusting the tension of said springs uniformly with respect to each other, means for guiding said compressing member and means for guiding said springs.

75 4. In a device according to claim 1, said driving mechanism further including a motor, and a

transmission gearing connected to said motor and said driving member respectively, said gearing comprising means for moving said member according to the law of conveyer motion, the means on said other element including a casing secured at one end to said other element, said springs being enclosed within said casing and guided thereby, means threadedly secured to the free end of said casing, said means being longitudinally adjustable with respect to said casing for adjusting the tension of said springs uniformly with respect to each other, and means on said casing for guiding said compressing member.

5 5. A drive for a shaking conveyer having a conveying member comprising a driving mechanism, said mechanism including a driving member which is moved according to the law of conveyer motion, and means connecting said driving member to said conveying member, said connecting means including elements hingedly connected to said driving member and conveying member respectively, a pair of aligned springs of equal strength and stroke, a member on one of said elements located between said springs, and means on the other element engaging the outer ends of the springs, said last member alternately compressing said springs in opposite directions, said springs being so dimensioned that in operation under high initial tension both springs remain elastic and bear against both of said elements, while under low initial tension each spring is relieved from load at least shortly after the other spring takes up the load, whereby the reciprocating and accelerating motions of the driving and connecting means and of said conveying member are modified and the change of force from one direction to the other takes place steadily and smoothly.

10 6. A drive for a shaking conveyer having a conveying member comprising a driving mechanism, said mechanism including a motor, transmission gearing connected to said motor, means connecting said gearing to said conveying member, said connecting means comprising a shaft, said shaft being hingedly connected to said gearing, a casing hingedly secured at one end to said conveying member, a pair of aligned springs of equal length and stroke enclosed by said casing, a piston on said shaft, said piston being slidably arranged within said casing between said springs and being guided by said casing, a member threadedly secured to the free end of said casing, said member being longitudinally adjustable with respect to said casing for adjusting the tension of said springs uniformly with respect to each other, said shaft slidably engaging said member and being guided thereby, means at the other end of said casing for guiding said shaft, said gearing comprising means for moving the piston according to the law of conveyer motion, said piston alternately compressing said springs in opposite directions, said springs being so dimensioned that in operation under high initial tension both springs remain elastic and bear against both of said elements, while under low initial tension each spring is relieved from load at least shortly after the other spring takes up the load, whereby the reciprocating and accelerating motions of the driving and connecting means and of said conveying member are modified and the change of force from one direction to the other takes place steadily and smoothly.

15 7. In a device according to claim 6 means at the other end of said casing for guiding said shaft.

8. A drive for a shaking conveyer having a conveying member comprising a driving mechanism, said mechanism including a motor, transmission gearing connected to said motor, means connecting said gearing to said conveying member, said connecting means comprising a rod, said rod being hingedly connected to said gearing, a casing secured at one end to said rod, a pair of aligned springs of equal length and stroke enclosed by said casing, a shaft hingedly connected to said conveying member, a piston on said shaft located between said springs, said casing longitudinally slideable with respect to said piston and guiding the same, a member threadedly secured to the free end of said casing and being longitudinally adjustable with respect to said casing for adjusting the tension of said springs uniformly with

respect to each other, said member slidably engaging said shaft and guiding the same, said gearing comprising means for moving said casing according to the law of conveyer motion, the end walls of said casing alternately compressing said springs in opposite directions, said springs being so dimensioned that in operation under high initial tension both springs remain elastic and bear against both of said elements, while under low initial tension each spring is relieved from load at least shortly after the other spring takes up the load, whereby the reciprocating and accelerating motions of the driving and connecting means and of said conveying member are modified and the change of force from one direction to the other takes place steadily and smoothly. 5 10 15

HANS CREMER.
